(57) **CLAIM**

The ornamental design for a mirror, as shown and described.

DESCRIPTION

FIG. 1 is a front, right, top perspective view of a mirror according to a first embodiment of our new design; FIG. 2 is a rear, bottom, left perspective view of the embodiment of FIG. 1;

FIG. 3 is a front view of the embodiment of FIG. 1; FIG. 4 is a rear view of the embodiment of FIG. 1; FIG. 5 is a right side view of the embodiment of FIG. 1; FIG. 6 is a left side view of the embodiment of FIG. 1; FIG. 7 is a top view of the embodiment of FIG. 1; FIG. 8 is a bottom view of the embodiment of FIG. 1; FIG. 9 is a front, right, top perspective view of a mirror according to a second embodiment of our new design; FIG. 10 is a rear, bottom, left perspective view of the embodiment of FIG. 9;

FIG. 11 is a front view of the embodiment of FIG. 9; FIG. 12 is a rear view of the embodiment of FIG. 9; FIG. 13 is a right side view of the embodiment of FIG. 9; FIG. 14 is a left side view of the embodiment of FIG. 9; FIG. 15 is a top view of the embodiment of FIG. 9; FIG. 16 is a bottom view of the embodiment of FIG. 9; FIG. 17 is a front, right, top perspective view of a mirror according to a third embodiment of our new design; FIG. 18 is a rear, bottom, left perspective view of the embodiment of FIG. 17;

FIG. 19 is a front view of the embodiment of FIG. 17; FIG. 20 is a rear view of the embodiment of FIG. 17; FIG. 21 is a right side view of the embodiment of FIG. 17; FIG. 22 is a left side view of the embodiment of FIG. 17; FIG. 23 is a top view of the embodiment of FIG. 17; FIG. 24 is a bottom view of the embodiment of FIG. 17; FIG. 25 is a front, right, top perspective view of a mirror according to a fourth embodiment of our new design;

(Continued)

FIG. 26 is a rear, bottom, left perspective view of the embodiment of FIG. 25;
 FIG. 27 is a front view of the embodiment of FIG. 25;
 FIG. 28 is a rear view of the embodiment of FIG. 25;
 FIG. 29 is a right side view of the embodiment of FIG. 25;
 FIG. 30 is a left side view of the embodiment of FIG. 25;
 FIG. 31 is a top view of the embodiment of FIG. 25;
 FIG. 32 is a bottom view of the embodiment of FIG. 25;
 FIG. 33 is a front, right, top perspective view of a mirror according to a fifth embodiment of our new design;
 FIG. 34 is a rear, bottom, left perspective view of the embodiment of FIG. 33;
 FIG. 35 is a front view of the embodiment of FIG. 33;
 FIG. 36 is a rear view of the embodiment of FIG. 33;
 FIG. 37 is a right side view of the embodiment of FIG. 33;
 FIG. 38 is a left side view of the embodiment of FIG. 33;
 FIG. 39 is a top view of the embodiment of FIG. 33;
 FIG. 40 is a bottom view of the embodiment of FIG. 33;
 FIG. 41 is a front, right, top perspective view of a mirror according to a sixth embodiment of our new design;
 FIG. 42 is a rear, bottom, left perspective view of the embodiment of FIG. 41;
 FIG. 43 is a front view of the embodiment of FIG. 41;
 FIG. 44 is a rear view of the embodiment of FIG. 41;
 FIG. 45 is a right side view of the embodiment of FIG. 41;
 FIG. 46 is a left side view of the embodiment of FIG. 41;
 FIG. 47 is a top view of the embodiment of FIG. 41; and,
 FIG. 48 is a bottom view of the embodiment of FIG. 41.
 The broken lines illustrating portions of the mirror form no part of the claimed design.
